UNITED STATES PATENT OFFICE.

CHARLES D. KARR, OF HOLLAND, MICHIGAN.

APPARATUS AND PROCESS FOR FABRICATING SPRING ASSEMBLIES.

Application filed September 30, 1926. Serial No. 138,742.

This invention relates to the process and apparatus for fabricating spring assemblies.

One of the objects of the invention is the provision of a new and improved method of 5 weaving or fabricating spring assemblies.

Another object of the invention is the provision of a new and improved mechanism for assembling springs to form cushion and mattress spring assemblies and the like.

10 A further object of the invention is the provision of a new and improved apparatus for connecting an assembly of spiral springs together by weaving, threading or interlocking helical springs therewith.

15 Another object of the invention is the provision of new and improved means for fabricating spring assemblies, that is simple in construction, cheap to manufacture, easily assembled, efficient in operation, composed 20 of few moving parts, and that is not likely to become broken or get out of order.

Other and further objects and advantages 25 of the invention will appear from the following description taken in connection with the accompanying drawings, in which

Fig. 1 is a plan view of the device with parts broken away;

Fig. 2 is a transverse section on the line 2-2 of Fig. 1;

30 Fig. 3 is a longitudinal section on line 3-3 of Fig. 1;

Fig. 4 is a vertical section on line 4-4 of Fig. 1 with parts broken away;

Fig. 5 is a plan view of a portion of the 35 spring retaining platform or member with a spring assembly in position thereon;

Fig. 6 is a vertical section of the construction shown in Fig. 5, and

40 Fig. 7 is a plan view of the spacing members.

In the form of the device selected to illustrate one embodiment of the invention, the 45 numeral 10 designates the base or supporting frame on which the operating mechanism is mounted. The operating mechanism comprises a spring retaining plate, bed or platform 11 for holding the springs in position during the operation, a spring feeding device 12 and the weaving mechanism 50 designated generally by the reference character 13.

The spring retaining plate 11, which if desired may be integral with the lateral extension 14 of the base 10 but is shown as 55 being mounted thereon, is provided with suitable means for holding the spiral springs

15 in position while the assembly is being fabricated. Any suitable means may be employed for this purpose. The form shown is by way of example only and comprises 60 projections 16 arranged in rows transversely to the weaving mechanism 13.

The form or shape of these projections will depend on the form of the terminal loops of the spiral springs that are being 65 operated upon. In the form shown, the terminal loops or coils are angular. Consequently the spring retaining lugs or projections 16 are angular and the side walls of these lugs are undercut as shown at 70 70 whereby when the terminal coils are expanded to engage said lugs, the coils will be retained in upright position.

The arrangement of the lugs or projections will also be determined more or less 75 by the form or shape of the spiral springs employed in fabricating the assembly. They must, of course, be arranged in rows transversely to the weaving mechanism in order that the helical springs 20 may be woven 80 about the end or terminal coils 18 of the spiral springs 15, as will presently appear.

In the form of the spiral springs disclosed, the terminal coils 18 are angular and each is provided with an offset straight portion 85 19 and with an angular straight portion 21 at the opposite side of the coil whereby in assembling the springs, the angular portion 21 of one spring will be arranged opposite the offset portion of an adjacent spring so 90 that the straight portions 22 and 23 at each side of the offset 19 of each spring (see Fig. 5) will be in alinement with the straight portions 21 of the opposite spring in the adjacent row for receiving the helical spring 95 20. The lugs or projections 16 are cut away to provide sufficient space to accommodate the helical coils 20 about the straight portions 21 of the springs 15. The use of springs of this type, therefore, requires that 100 the spring holding or retaining means or lugs be also arranged in rows extending longitudinally of said weaving mechanism.

Grooves 25 may also be provided between the transversely extending rows for guiding 105 the helical springs 20 during the weaving operation. The depth of these grooves or their elimination entirely will depend on the height at which the springs are supported by the retaining means.

Suitable means are provided for weaving 110 or threading the helical springs 20 about

the terminal coils of the springs 15. One form of mechanism for accomplishing this function will now be described. The mechanism comprises essentially an endless belt 5 which is adapted to frictionally engage the helical springs to cause the same to rotate and be threaded or woven onto those portions of the springs supported in the path of the helicals.

10 As shown, the base 10 is provided at each end with supporting arms 250, within which are rotatably mounted the rollers 26 and 27 about which is trained an endless belt 29. The belt 29 is operated by any suitable 15 mechanism as by the pulley 30 on shaft 40 of the roller 27. The upper and lower runs of the belt 29 are held in parallel relation adjacent to each other by a pair of rollers 31 and 32 adjacent to the roller 26 and a 20 pair of rollers 33 and 34, adjacent to the roller 27. Suitable means may, if desired, be provided for adjusting the rollers of each pair toward and from each other as may be necessary or desirable.

25 The upper and lower runs of the belt are held in spaced relation by suitable spacer members. As shown, the spacer members or fingers 35 and 36 are rigidly secured to a body portion 39 which is offset downwardly from said fingers and is rigidly secured to the lateral extension 41 of the supporting frame 10, see Fig. 2. These spacer members or fingers are spaced apart a distance slightly greater than the diameter of the 30 helical springs 20 and their thickness is slightly less than the diameter of said helical springs whereby the belt will engage the helical springs at each side of said spacers for rotating the same as will presently appear. The outer fingers 36 are shown as being very narrow. If desired, a plurality of narrow fingers may be employed instead of the wide intermediate ones. The attached ends of the spacers are tapered as at 42, 35 that is, thickened at their inner or supporting ends to cause the upper and lower runs of the belt to flare outwardly for forming funnel shaped openings for receiving the ends of the helical springs from the feeding 40 mechanism. The inner or supporting ends of the fingers also have their adjacent edges bevelled as shown at 28 as clearly shown in Figs. 1 and 7 for guiding the helical springs to the spaces 51 between the fingers as will 45 presently appear. The number of spacers employed will depend on the number of helical springs necessary for fabricating the 50 spring assembly.

Means are provided for feeding or delivering the helical springs to the weaving mechanism. Preferably this device comprises a box like member 43 which is adapted to be slid to and from the weaving mechanism on the guides 44. The member 43 55 preferably comprises a lower section 45 and

an upper section 46, see Fig. 4, which is hinged to the lower section at one side by hinges 47. The lower section is provided with grooves 48, one for each helical to be used. Each groove is provided with a pin 49 arranged across the groove at the angle of the coils of the helical for feeding the helicals forwardly when the same are rotated by the belt. Each groove 48 is in alignment with the spaces 51 between the fingers 35, 36 and the corresponding groove 25 between the projections 16 on the spring retaining device 11.

If desired, rollers may be employed for engaging either the upper or the lower run 80 of the belt or both for holding the belt in engagement with the helical springs. As shown, a roller 50 is mounted at each side of the space between the fingers and a roller 60 at each side of this space below the belt 85 for holding both runs of the belt against the corresponding spring. The rollers 31, 32, 33 and 34 at each end of the belt are sufficiently close to the end springs as to 90 permit the end rollers 50 and 60 to be dispensed with. The rollers 50 and 60 are tapered at their ends adjacent to the thickened ends of the fingers as at 61 to permit the belt edges to flare outwardly as clearly 95 shown in Fig. 2. Their outer ends are journaled in suitable plates 62 and 63 and their inner ends are journaled, the lower rollers in the vertical connecting portion of the spacer support and the upper rollers in lugs 100 64 on the fingers 35.

In the operation of the device, the helicals are placed in the grooves 48 with their ends extending inwardly or forwardly beyond the forward end of the box member, the weaving mechanism is started, and the box member 105 43 is pushed forwardly to insert the ends of the helicals between the flaring sides of the belt 29. As soon as the ends of the helicals come in contact with either or both runs of the belt, they will be rotated by the movement of said belt and the engagement of the coils of the helical with the pins 49 will cause the helicals to advance across the belt into the aligned grooves 25 in the spring holding 110 device 11 for engaging the straight portions 23, 21 and 22 of said springs.

The belt 29 may be of any suitable width but its width must be less than the length of the helicals in order that they may reach from the pins 49 into engagement with the spirals, otherwise there would be no means for advancing said helicals. As soon as the helicals engage the terminal coils of the spirals, they will be advanced along the grooves 25 and be woven about the straight 115 portions 23, 21 and 22 of said spirals until their outer ends pass beyond said belt.

By means of this arrangement, all the helicals are woven about the terminal coils of the spirals 15 simultaneously. Should any 120

helical become jammed or blocked temporarily, it will not interfere with the movements of the remaining ones. After the cause has been removed, it may be woven into position.

5 After the helicals have been applied to one side of the assembly, the latter is reversed, the spirals fitted over the projections and the process repeated for inserting or weaving the helicals about the opposite ends of the spirals, 10 for completing the assembly.

In the embodiment of the invention shown on the drawing, the helicals are engaged on opposite sides by the belt. Since the two runs of the belt move in opposite directions any tendency to move the helicals laterally by one run of the belt will be counteracted by the tendency to move the same in the opposite direction by the other run of the belt, hence in this form of the construction 15 it is not necessary to provide the weaving mechanism with means for guiding the helicals.

It is preferable, however, to provide guides such as the spaces between the fingers 25, 26 in order that the helicals may be properly guided, whether they be engaged by one or both runs of the belt.

While in the form of the device shown on the drawing the helicals are advanced between the runs of the belt, it is understood that the construction may be otherwise, it being only necessary that one or both runs of the belt engage the helicals for rotating the same.

35 While the apparatus is disclosed as being employed for connecting spiral springs by weaving helicals about straight portions of the same, it is understood that the form of the springs and the shape of the connecting portions are immaterial as springs or wire units of any type may be assembled by arranging the springs or wire units in such a manner that portions of the same may be held in the paths of the advancing helicals.

45 It is thought from the foregoing taken in connection with the accompanying drawings that the construction and operation of my device will be apparent to those skilled in the art, and that various changes in size, shape, proportion and details of construction may be made without departing from the spirit and scope of the appended claims.

I claim as my invention:

55 1. A method of fabricating spring structures which consists in arranging a plurality of spiral springs in rows and connecting said rows together by simultaneously weaving helical springs into said spiral springs.

2. A method of fabricating spring assemblies which consists in arranging spiral springs in rows, weaving a plurality of helical springs about the lower end portions of the springs of each row, reversing said spiral springs and weaving a plurality of helical springs about the end portions of said

spiral springs opposite to said first named end portions.

3. A method of fabricating spring assemblies, which consists in arranging spiral springs in adjacent parallel rows and weaving a helical spring about end portions of the spiral springs of adjacent rows by a continuous rotary movement of said helical spring. 70

4. In a device for fabricating spring assemblies comprising a platform, spring retaining members thereon, a feeding device for containing helical springs and means for continuously rotating said helical springs for advancing the same between rows of said 80 retaining members. 75

5. In an apparatus for fabricating wire assemblies, means for supporting wire units in rows, with portions of said units adjacent each other, a feeding device for holding a 85 helical, means for rotating and advancing said helical to cause the same to encircle the said portions of said units adjacent to each other.

6. In an apparatus for fabricating spring assemblies, a weaving mechanism comprising a belt, means for moving the same, and means for holding a helical in engagement with said belt for rotating said helical. 90

7. In an apparatus for fabricating spring assemblies, an endless belt, means for operating said belt, a plurality of spacer members between the runs of said belt, feeding mechanism adapted to direct a plurality of helicals into the space between said spacers 100 and into frictional engagement with said belt and means on said feeding mechanism for advancing said helicals when the same are rotated by said belt. 105

8. In an apparatus for fabricating spring assemblies, a feeding device comprising a box like member provided with a plurality of parallel grooves for receiving helicals and a projection extending inwardly from the wall of each of said grooves for engaging 110 the coils of said helicals for advancing the helicals when the same are rotated.

9. In an apparatus for fabricating spring assemblies, a belt spacing device comprising a plurality of spacer members adapted to 115 be inserted between the runs of an endless belt, said spacers being provided with oppositely inclined surfaces adjacent one end for flaring the edges of said belt at one side thereof. 120

10. In an apparatus for fabricating spring assemblies, means for rotating a helical comprising an endless belt, a support for said helical and means for holding said belt in engagement with said helical during the 125 operation of said belt, said means comprising a roller having a tapered end. 125

11. An apparatus for fabricating spring assemblies comprising a support, means on said support for holding spiral springs, 130

weaving mechanism for weaving helicals about portions of said springs and means for rotating said helicals, said means comprising a member moving in one direction and in contact with one side of each of said helicals.

12. In an apparatus for fabricating spring assemblies, means for holding a plurality of spiral springs in rows, a feeding device containing a plurality of helicals, weaving mechanism comprising an endless belt, spacer members between the runs of said belt and spaced apart to receive said helicals, said

spacer members being increased in thickness and inclined at their inner ends to hold the inner edges of the belt flared outwardly, a 15 plurality of rollers above and below the upper and lower runs of said belt, respectively, said rollers being tapered to correspond with the flare of said belt, and means in said device for advancing said helicals 20 when the same are advanced.

In testimony whereof I affix my signature.

CHARLES D. KARR.
